UNITED STATES PATENT OFFICE

FRANK E. PFEIFFER, OF DAYTON, OHIO, ASSIGNOR TO THE EGRY REGISTER COMPANY, OF DAYTON, OHIO, A CORPORATION OF OHIO

AUTOGRAPHIC REGISTER

Application filed May 4, 1931. Serial No. 534,874.

This invention relates to improvements in autographic registers, and has for its object to provide means cooperating with the writing table of the register for aligning the 5 sheets of paper at creases in the sheets of paper.

It is an object of this invention to provide, in connection with an autographic register, a writing table therefor, which has a slot 10 therein through which sheets of paper are fed, one edge of the slot being made more or less sharp and provided with a plate extending over the slot to hold the sheets of paper in contact with the table and being 15 provided, adjacent the slot beneath the table, with means cooperating with the sharp edge of the table at the slot for aligning the sheets of paper.

It is an object of this invention to provide, in connection with a writing table having means thereon for aligning the creased sheets of paper, mechanical means for feeding and discharging the sheets of paper, and means operated by said mechanical 25 means for operating the aligning means.

It is also an object of this invention to provide, in connection with an autographic register, means for feeding by predetermined cycles of operation strips of paper 30 of different lengths, and aligning said strips of paper.

It is also an object of this invention to provide, in connection with an autographic register adapted to feed strips of paper 35 having transverse creases therein, means for feeding the sheets of paper during a certain cycle of operation, means for aligning the sheets at the end of the cycle of operation, and means for removing the aligning means 40 at the beginning of a cycle of operation to replace it after a short interval of operation.

These and other advantages will appear from the following description taken in connection with the drawings, in which there 45 is shown a preferred embodiment of this invention.

Referring to the drawings:

Figure 1 is a top plan view of an autographic register.

Figure 2 is a top plan view of the casing 50

with the cover and writing table in elevated position and in section.

Figure 3 is a vertical longitudinal section through the casing showing the aligning means and the means for operating the 55 aligning means.

Figure 4 is a section on the line 4—4 of Figure 3 with the cover and writing table in elevated position.

Figure 5 is a fragmentary section through 60 the casing showing the strip-aligning means in a position reverse to that shown in Figure 3.

This autographic register has the usual casing consisting of side walls 1, a front end 65 2, a rear end 3 and a bottom 4. These parts are made of any suitable material. In the front end of the register and on each side thereof are studs 5 adapted to support, in connection with the front end of 70 the casing, a front cover 6, which has on the under side thereof, adjacent each lateral edge, hooks 7 to engage beneath the studs 5 for holding the cover firmly on the end of the casing.

These hooks project rearwardly and engage the studs when the cover is pushed rearwardly on the front end of the casing. For holding the cover in closed position with the hooks 7 in engagement with the 80 studs 5, a lock 8 is provided on the front end of the casing for engagement with a lug 9 on a turned-down part of the cover 6 immediately above the front end of the 85 casing.

In order to properly guide sheets of paper that are stored in the front end of the casing and hold them in position, a weight or frame 10 is provided which is pivoted to a support plate 11 suitably attached to the under side of the cover 6. A slot may be provided in the end for receiving the strips of paper into a chamber 12 in the casing, or they may be inserted through the top 95 when the cover is removed. In the rear end of the casing is a chamber 13 in which the strips of paper are folded before they are ejected for use over the table of the autographic register. Extending across the 100

casing at different points are cross rods or bars 14.

On one of these bars, near the rear end, are pivoted brackets 15 which are attached 5 to and support in a pivoted manner on this rod 14 a writing table 16, the front end of which is supported by studs 17 on the sides of the casing. In the writing table, between the center thereof and the rear end, is a 10 slot 18. The table along the front edge of the slot 18 is sharpened to form a sharp edge 19 for engaging creases in the paper for aligning purposes. On top of the writing table, immediately above the slot 18, is a 15 presser plate 19a which tends to hold the strips of paper at this point in close relation to the upper surface of the writing table so that at the proper time the strips of paper may be aligned by the sharp edge 19 20 and the frame beneath the writing table co-operating therewith.

This frame is pivoted immediately to the rear of the slot 18 and consists of a cross rod 20, which has extending from each end 25 thereof arms 21. Each arm is bent out to form an axle member 22 in alignment with each other and parallel with the cross rod 20. These axles are pivoted to the writing table by means of bearing brackets 23, suitably attached to the under side of the table. 30

To the arms 21 and slightly removed from the cross rod 20 is a second cross rod 24. The cross rods 20 and 24 form, in connection with the arms 21, a slot through which 35 the strips of paper pass before they pass out through the slot 18 in the writing table. On the cross rod 24 is a spacer block 25, which serves to hold the frame in spaced relation to the under side of the writing 40 table when the frame is in its most forwardly swung position, as shown in Figure 3. This stop prevents the strips of paper being jammed against the under side of the table.

Extending from one of the axles 22 is an 45 offset arm 26 to which one end of a spring 27 is attached, while the other end of the spring is attached to the under side of the writing table. The purpose of this spring is to hold the frame in the position shown 50 in Figure 3. On the arm 21 remote from the offset arm 26 is a spindle 28, on which is pivotally mounted one end of a link 29, the other end of which is pivotally attached to a slide plate 30, which is slidably held 55 on the under side of the writing table by means of a plurality of guide clips 31. It is by means of this slide plate that the frame is shifted from the position shown in Figure 3 to the position shown in Figure 60 5.

Extending downwardly from the slide plate is an abutment 32, against which a finger, later to be described, abuts for shifting the plate to rock the frame carrying the 65 cross rods 20 and 24. Suitably located in

the front end of the casing is an operating shaft 33, which has on one end outside of the casing a handle 34 by which the shaft is rotated. On the shaft within the casing are two discs 35, which have on their peripheries serrations 36 for feeding the strips of paper. There is also on this shaft, adjacent one side of the casing, a gear 37 which meshes with a pinion 38 immediately above the gear on a roller 39. This roller has serrations 40 thereon, which cooperate with the serrations 36 in feeding the strips of paper. 70

The roller 39 is pivotally mounted at 80 each end in a plate 41, each plate having slots 42 therein to receive pins or studs 43 in the sides of the casing for guiding the plates in vertical movements. The lower end of each plate is turned in to form a bench-like structure 44, and immediately below each turned-in end of each plate 41 is a bracket 45, which has a projection 46 thereon beneath the member 44. Extending through the bench-like structure and the projection 46 is a bolt 47, which has on its 90 lower end a nut and between the nut and the projection a spring 48 which tends to hold the plates in lowered position with the roller 39 resting upon the discs 35 for gripping and feeding the strips of paper when 95 the handle is rotated.

On the shaft 33, inside the casing and remote from the gear 37, is a segmental gear 49, as shown in Figure 3. This gear is 100 adapted to mesh with another segmental gear 50, suitably pivoted to the side of the casing adjacent which the segmental gear 49 is located. This gear 50 is supported on a shaft 51 in the side of the casing. Extending from one edge of the segmental gear 50 is a finger 52, which is attached thereto by screws 53 and adapted to contact with the abutment 32 for moving the frame from its forward position, as shown 105 in Figure 3, to its rearward position, as 110 shown in Figure 5.

At the beginning of each cycle of operation the parts are in the position shown in Figure 3. At this time the segmental gears 49 and 50 are in engagement. By operating the handle in a counter-clockwise direction the segmental gear 50 is caused to rotate in clockwise direction. This movement of the segmental gear 50 causes the finger 52 to contact the abutment 32 and push the slide plate 30 in a rearward direction so that the frame member is pushed backward from the position shown in Figure 3 to that shown in Figure 5. As soon as the segmental gear 49 passes out of engagement with the segmental gear 50 the spring 48 causes the frame member to assume again the position shown in Figure 3. The frame member keeps this position until the end 125 130

of the operation and the beginning of a second cycle of operation.

During the time the strips of paper are being fed through the slot 18 the strips are not aligned but move freely through the slot until the creases in the strips reach the sharp edge 19 on the writing table. At this time the paper creases will engage the sharp edge 19 so that the feed members, consisting of the discs and the roller 39, will not feed the paper forward but will rotate without discharging or feeding the strips of paper.

By regulating the position of the slot and the adjacent frame the length of the strips of paper fed may be varied. The feeding of the strips of paper depends upon the creases. If the creases are located close to each other short strips of paper are fed. If the creases are further apart longer strips of paper are fed. The strips of paper will be fed through the slot in the position shown in Figure 3 until the creases reach the slot. The creases as shown in Figure 3 are in the slot and the paper in the position there shown cannot be fed. It is to be understood that the frame structure located adjacent the slot has no aligning effect except when the creases are in the slot in engagement with the sharp edge on the table.

There is also pivotally mounted on the rear end of the casing, on a cross rod 14 immediately adjacent the rear wall, a cover 55, by means of brackets 54 attached to the lower surface thereof. These brackets are suitably attached to the cover and pivotally supported on one of the cross rods 14 immediately adjacent the rear of the casing. The cover has therein suitable writing space 56 immediately above the strips of paper being fed over the writing table. On the front end of the cover is a rounded housing 57, which incloses the roller 39.

Adjacent the handle and in one side of the casing is a stop member 58. This stop member is used for stopping the rotation of the handle at the end of each cycle of operation. It is shown in Figure 2 with the handle engaged beneath it in stopped position. By pushing the stop 58 inwardly the handle may be released so that it may be operated for another cycle of operation, at the end of which the handle is again stopped by the stop 58.

In order to prevent the backward rotation of the operating shaft 33 there is provided on one of the cross rods 14 a pawl 59, which is held in engagement with the teeth of the gear 37 by means of a spring 60 on the rod on which the pawl is mounted. To one side of the main casing is a housing 61 for carbon paper, which is mounted upon a shaft 62 extending longitudinally through the housing. On this shaft 62 is a plate 63, held in engagement with one end of the carbon paper by means of a spring 64. On

the side of the casing opposite the carbon housing is a plate 65 pivoted at the point 66 to one side of the casing and held by means of a latch 67. This plate is adapted to hold between it and the side of the casing the ends of the carbon sheets that are fed across the writing table between the strips of paper.

The strips of paper are indicated by the numeral 68. The creases therein are indicated by the numeral 69.

It will be understood that the rolls are slightly spaced so as to frictionally engage the sheets sufficiently to move them and to move by the sheets when the sheets are restrained by being aligned on the transverse creases.

I desire to comprehend within my invention such modifications as may be embraced within my claims and the scope of my invention.

Having thus fully described my invention, what I claim as new and desire to secure by Letters Patent, is:

1. In an apparatus for feeding and aligning a plurality of superimposed strips of paper having transverse creases therein, a fixed table having an edge thereon, means for pulling the strips over the table, and means operable at a certain stage in the operation of the apparatus for moving and holding the strips against the edge whereby the strips are aligned when the creases reach the edge.

2. In an apparatus for feeding and aligning superimposed strips of paper having transverse creases therein, a fixed table having an edge thereon, rollers for pulling the strips over the table, and means operable at a certain stage in each cycle of operation of the apparatus for moving and holding the strips against the edge whereby the strips are aligned when the creases reach the edge.

3. In an apparatus for feeding and aligning superimposed strips of paper having transverse creases therein, a table having an edge thereon, roller means for pulling the strips and causing them to travel over the table, means operable to hold the strips against the edge whereby the travel of the strips is stopped and they are aligned when the creases reach the edge, and means operated by the roller means to shift the last-named means whereby the position of the strips with relation to the edge is changed so that the creases will pass around the edge and the travel of the strips be resumed.

4. In an apparatus for feeding and aligning superimposed strips of paper having transverse creases therein, a table having an edge thereon, means for engaging said strips and causing them to travel over the table, means operable to hold the strips against the edge whereby the creases reach the edge the travel of the strips is stopped

and they are aligned, and means operated by said first-named means to shift the second-named means whereby the position of the strips with relation to the edge is 5 changed so that the creases will pass around the edge and the travel of the strip be resumed.

5. In an apparatus for feeding and aligning superimposed strips of paper having 10 transverse creases therein, strip-feeding means operable on the strips during a whole cycle of operation, and means during the cycle of operation and while the feeding means is operating on the strips for engaging 15 the strips at their creases for aligning them.

6. In an apparatus for feeding and aligning strips of paper, strip-feeding means operable on the strips during the whole of a 20 cycle of operation, means operating during the cycle of operation and in opposition to the strip-feeding means to align the strips, and means operable at a certain stage in the 25 cycle of operation to release the aligning means.

7. In an apparatus for feeding and aligning strips of paper, strip-feeding means operable on the strips during the whole of a 30 cycle of operation, and means operating on the strips against the pull of the strip-feeding means for aligning the strips.

8. In an apparatus for feeding and aligning strips of paper, strip-feeding means operable on the strips during the whole of a 35 cycle of operation, means operating on the strips against the pull of the strip-feeding means for aligning the strips, and means operable at a certain stage in the cycle of operation to release the aligning means.

40 9. In an apparatus for feeding and aligning strips of paper, strip-feeding means operating on the strips during the whole of a cycle of operation, means operating on the strips against the pull of the strip-feeding 45 means to align the strips, and means operated by the strip-feeding means at a certain stage in the cycle of operation to release the aligning means.

10. In an apparatus for feeding and aligning 50 strips of paper, a pair of strip-feeding rollers operating on the strips during the whole of a cycle of operation, means comprising a pivoted frame operating against the pull of the strip-feeding means to align the strips, and means operated by the strip-feeding rollers at a certain stage in the cycle of operation to rock the frame, whereby the strips are no longer acted on for alignment but are fed by the feeding rollers.

60 11. In an apparatus for feeding and aligning strips of paper having transverse creases therein, a pair of strip-feeding rollers operating on the strips during the whole of a cycle of operation, a table having an edge 65 over which the strips are fed, means coop-

erating with the edge to engage the strips along the creases to hold the strips against the pull of the rollers and align the strips, and means to operate the first-named means whereby the strips may be again fed by the 70 rollers.

12. In an apparatus for feeding and aligning strips of paper having transverse creases therein, a pair of strip-feeding rollers operating on the strips during the whole of a 75 cycle of operation, a table having an edge over which the strips are fed, pivoted frame means cooperating with the edge to engage the strips along the creases to hold the strips against the pull of the rollers and 80 align the strips, and means to operate the first-named means whereby the strips may be again fed by the rollers.

13. In an apparatus for feeding and aligning strips of paper having transverse creases 85 therein, a pair of strip-feeding rollers operating on the strips during the whole of a cycle of operation, a table having an edge over which the strips are fed, means co-operating with the edge to engage the strips 90 along the creases to hold the strips against the pull of the rollers and align the strips, and lever and link means operated by the rollers to operate the first-named means whereby the strips may be again fed by the 95 rollers.

14. In an apparatus for feeding and aligning strips of paper having transverse creases therein, a pair of strip-feeding rollers operating on the strips during the whole of a 100 cycle of operation, a table having an edge over which the strips are fed, pivoted frame means cooperating with the edge to engage the strips along the creases to hold the strips against the pull of the rollers and 105 align the strips, and lever and link means operated by the rollers to operate the first-named means whereby the strips may be again fed by the rollers.

15. In an apparatus for feeding and aligning strips of paper having transverse creases therein, a pair of strip-feeding rollers operating on the strips during the whole of a cycle of operation, a table having an edge over which the strips are fed, means pivoted 110 to the table cooperating with the edge to engage the strips along the creases to hold the strips against the pull of the rollers and align the strip, and means to operate the first-named means to release the strips 115 whereby the strips may be again fed by the rollers.

16. In an apparatus for feeding and aligning strips of paper having transverse creases 120 therein, a pair of strip-feeding rollers operating on the strips during the whole of a cycle of operation, a table having an edge over which the strips are fed, pivoted frame means pivoted to the table cooperating with the edge to engage the strips along the 125 130

creases to hold the strips against the pull of the rollers and align the strips, and lever and link means operated by the rollers to operate the first-named means to release the strips whereby the strips may be again fed by the rollers.

17. In combination, in an autographic register having a plurality of superimposed sheets having superimposed transverse creased portions, a writing table against one edge of which said creases engage for aligning the sheets, a swinging frame for moving said sheets beneath the table back of the aligning edge to cause the sheets at the 10 creased portions to engage the edge of the table after alignment, and ejecting means at the other end of the table engaging the sheets sufficiently to move them until the creases in the sheets move to aligning position, whereupon the ejecting mechanism will 20 continue to move while the sheets are stationary.

18. In combination, in an autographic register having a plurality of superimposed sheets having superimposed transverse creased portions, a writing table against one edge of which said creases engage for aligning the sheets, a swinging frame for moving said sheets beneath the table back of 25 the aligning edge or to one side of the aligning edge to permit the sheets to slip over the edge of the table after alignment, ejecting means at the other end of the table engaging the sheets sufficiently to move them until the creases in the sheets move to aligning position, whereupon the ejecting mechanism will 35 continue to move while the sheets are stationary, and means interconnecting said ejecting means and swinging frame, 40 whereby the swinging frame will be moved to non-aligning position when the ejecting means starts to eject to move the sheets out of the register.

19. In an apparatus for feeding and aligning strips of paper in combination with a 45 table, means adjacent one end of the table for feeding the strips over the table, means adjacent the other end of the table to align the strips, said aligning including a pivoted frame, means tending to hold the frame in 50 aligning position, and segmental gears operated by the feeding means to move the frame out of aligning position.

20. In an apparatus for feeding and aligning strips of paper in combination with a table, means adjacent one end of the table for feeding strips of paper over the table, a frame supported adjacent the 55 other end of the table and cooperating with the table for aligning the strips, means tending to hold the frame in aligning position, and means to move said frame out of aligning position, said means comprising a pair 60 of interacting segmental gears, one sup-

ported and operated by the feeding means and the other connected to the frame.

21. In an apparatus for feeding and aligning strips of paper in combination with a table, means for feeding strips of paper comprising a shaft, a movable frame cooperating with the table to align the strips and means for moving the frame, said means consisting of a segmental gear on the shaft, a second segmental gear supported underneath the table and adapted to be engaged and operated by the first-named segmental gear, and a link connecting the second segmental gear to the frame. 70

22. In an apparatus for feeding and aligning strips of paper in combination with a table, means for feeding strips of paper over the table, said means consisting of a shaft having a plurality of serrated discs thereon and a roller having serrations thereon cooperating with the discs to grip the strips, and means operatively connected to the shaft for aligning the strips in cooperation with the table while the feeding means is operating on the strips. 80

23. In an apparatus for feeding and aligning strips of paper in combination with a table, means for feeding strips of paper over the table, said means consisting of a shaft having a plurality of serrated discs 90 thereon and a roller having serrations thereon cooperating with the discs to grip the strips, and movable frame means on the table and operatively connected to the shaft for aligning the strips in cooperation with 95 the table.

24. In an apparatus for feeding and aligning strips of paper in combination with a table, means to feed strips of paper over the table consisting of a shaft having serrated discs thereon and a resiliently mounted roller resting on said discs, and means cooperating with the table for aligning the strips while the feeding means is acting on the strips to feed them. 105

25. In an apparatus for feeding and aligning strips of paper having transverse creases therein in combination with a table, means acting on the strips continually to feed them over the table, said means consisting of a shaft having discs thereon and a resiliently mounted roller bearing against the discs, means cooperating with the table to grip the strips along a crease, whereby the operation of the feeding means will align 110 the strips, and means operated by said shaft to move the cooperating aligning means, whereby the operation of the feeding means will feed the strips of paper. 115

26. In an apparatus for feeding and aligning strips of paper having transverse creases therein in combination with a table, means for feeding strips of paper over the table consisting of a shaft having discs thereon and a resiliently mounted roller 120

130

bearing against the discs, a frame cooperating with the table to grip the strips along a crease, whereby the operation of the feeding means will align the strips, and means 5 to move the frame whereby the operation of the feeding means will feed the strips of paper, said last-named means consisting of a segmental gear on the shaft, a second segmental gear mounted beneath the table and 10 adapted to be operated by the first-named segmental gear, and a link connecting the second-named segmental gear to the frame.

27. The method of feeding a plurality of superposed transversely creased strips of 15 paper so as to re-align printed or other matter thereon, which comprises causing the strips of paper to move at an obtuse angle around a sharp edge until the creases reach the sharp edge, bending the strips at an 20 acute angle about the sharp edge, and applying pull on the strips of paper whereby they are aligned.

28. The method of feeding a plurality of superposed strips of paper so as to align 25 printed or other matter thereon, which comprises forming transverse creases in the strips, exerting a pull on the strips of paper and causing said strips to move at an obtuse angle around a sharp edge until the creases 30 reach the sharp edge and said strips are aligned as to the printed or other matter thereon, and then increasing the angle of the path of travel of the strips whereby the creases will be permitted to move by the 35 sharp edge.

29. The method of feeding a plurality of superposed transversely creased strips of paper so as to re-align printed or other matter thereon, which comprises exerting a pull 40 on the strips of paper whereby the strips are caused to move at an obtuse angle around a sharp edge until the creases reach the sharp edge and the strips are aligned as to the printed or other matter thereon, 45 and increasing the angle of the path of travel of the strips adjacent the sharp edge whereby the creases will move by the sharp edge.

30. The method of feeding a plurality of 50 superposed transversely creased strips of paper so as to re-align printed or other matter thereon, which comprises exerting a pull on the strips of paper and causing the strips to move at an obtuse angle around a sharp 55 edge until a succeeding crease reaches the sharp edge, continuing the pull to align the strips as to the printed matter thereon, and then increasing the angle of the angularity of movement of the strips around the sharp 60 edge to permit continued movement of the strips due to the pull.

In testimony whereof, I affix my signature.

FRANK E. PFEIFFER.
